UNITED STATES PATENT OFFICE.

EDWARD GOEHST, OF CHICAGO, ILLINOIS.

FLOOR.

SPECIFICATION forming part of Letters Patent No. 662,376, dated November 20, 1900.

Application filed December 12, 1899. Serial No. 740,093. (No model.)

To all whom it may concern:

Be it known that I, EDWARD GOEHST, a citizen of the United States, residing at Chicago, Illinois, have invented certain new and useful 5 Improvements in Floors, of which the following is a specification.

My improvements relate particularly to the method and means of binding together hard-wood flooring-boards to form a border for a 10 floor, the center boards of which may be of soft wood and laid in the usual manner.

In the building or laying of floors as at present carried on it is common to form a border of fancy or hard wood, sometimes different-colored woods being used to give an ornamental finish or striped effect, while the center of the floor, which is covered by a rug or carpet, is laid with soft boards placed side by side in the usual manner. In laying the 15 boards forming the border it is necessary to miter the corners, and in order that the proper finish may be given the boards must be planed after being laid to get rid of all ridges along the cracks and uneven places. This work 20 must be done by hand and is therefore expensive and troublesome, and it is to avoid these difficulties and provide for a better finish than can be secured by hand-work that I have designed my improvements.

30 The manner of carrying out my improvements is shown in the accompanying drawings, which form a part of this application, and in which—

Figure 1 is a bottom plan view of a section 35 of a border made in accordance with my invention. Fig. 2 is an edge view of the same. Fig. 3 is a perspective view of the same inverted, showing one of the wedges partly withdrawn; and Fig. 4 is a detail, on a larger 40 scale than the preceding views, showing the relative positions of the wedge and a board to which it is fitted, the view being in perspective and only a portion of the board and the wedge being shown.

45 Referring to the drawings, *a* represents ordinary tongue-and-grooved floor-boards, which are placed in juxtaposition to form a section of a border for a floor, the ends being suitably mitered to fit adjoining sections of a border. In 50 the under side of these boards and extending transversely therethrough are formed at opposing angles *b*, having beveled

edges and with a depth about one-third the thickness of the boards. The groove *b* is formed with a taper, the wider end of which 55 is in the outer edge of the border *a'*, which abuts against the skirting or mop-board of a room, and the cross-diameter of the groove is greater at its top than at its bottom or open portion. Closely fitting the groove *b* is a beveled-edge wedge *c*, which when driven home 60 brings the boards *a* close together and prevents them from being displaced by lateral or end pressure and when two wedges are used, as shown, also prevents the separation 65 of the boards by strain or pressure at right angles to their length. In practice the grooves will be formed in the boards at opposing angles, so that if continued they will meet, and wedges will be inserted at intervals 70 throughout the length of the boards, so that the latter may be effectively bound together. When the border is placed in position in the floor, with the edge *a'* to the mop-board, it will be impossible to displace or dislodge the wedges, as will be readily understood. 75

For some classes of work and as an additional means of binding together the boards forming the border I bore transversely there-through openings in which are inserted bolts 80 *d*, having threads on one end to receive nuts *e*, which when screwed up will force together boards the edges of which may be irregular and hold them securely in position. 85

If desired, the wedges may be dipped in glue before being inserted in position.

In practice the borders will be made at the mill in suitable lengths, and after being formed or the boards bound together in the 90 manner described the upper surface will be run through a planer and the ends mitered by machinery, so that they will be ready to lay as complete or integral parts of the floor. By the use of my improvement it will be unnecessary to nail each course of boards forming the border to the supporting-joist or the first floor, (in the case of a double floor,) as it will be sufficient to nail the board forming the inner course of the border. If preferred, the boards forming the border may be fitted, mitered, and planed in the mill or factory, then knocked down and shipped in such shape to the place where they are to be laid, 95 100

the wedges and bolts being supplied for the purpose of securing them together in the manner described.

Having thus described my invention, what I claim as new, and desire to obtain by Letters Patent, is—

A border for floors, composed of a plurality of boards having tapering grooves formed in their lower sides, said grooves having bevelled sides, and extending transversely through

said boards at opposing angles to each other, and wedges adapted to fit said grooves, substantially as set forth.

In testimony whereof I affix my signature in the presence of two witnesses.

EDWARD GOEHST.
